UNITED STATES PATENT OFFICE.

GEORGE W. BILLINGS, OF CLEVELAND, OHIO.

INITIAL LIGHTING DEVICE FOR GASOLINE-VAPOR STOVES.

SPECIFICATION forming part of Letters Patent No. 398,691, dated February 26, 1889.

Application filed January 24, 1889. Serial No. 297,467. (No model.)

To all whom it may concern:

Be it known that I, GEORGE W. BILLINGS, of Cleveland, in the county of Cuyahoga and State of Ohio, have invented new and Improved Initial Lighting Devices for Gasoline-Vapor Stoves; and I do hereby declare that the following is a full, true, and exact description thereof.

My invention consists of devices arranged for the initial lighting for heating of the generators of vapor-burners, by which means the fluid is burned without smoke, thus avoiding the accumulation of soot on the burner and other parts or articles about the stove brought in contact with the smoke.

That the device may be fully understood, reference will be had to the annexed specification and the accompanying drawings, in which—

Figure 1 is a vertical side elevation of a burner and a section through the stand-pipe and initial lighting device on line *x x*, Fig. 2. Fig. 2 is a plan view of the initial lighting device having the stand-pipe inserted but detached from the burner.

Like letters of reference denote like parts in the drawings and specification.

In Fig. 1 A represents the stand-pipe, to which is attached the vapor-burner B.

C is the inlet-tube, and D the needle-valve thereof.

E is the deflector, which for support has its arm F pivoted to the side of the needle-valve D. (This pivotal connection is not shown in the drawings.) Said deflector can be swung so as to be just in front of the needle-valve D, as indicated in Fig. 1, or moved to the side thereof, when a free passage from the needle-valves to the combustion-chamber of the burners ensues.

As shown, the deflector is set or swung between the needle-valve and the inlet-tube C, in which case the discharge from the needle-valve is deflected from a straight course to that indicated by the arrow 1, which leads to the initial lighting device underneath, which consists of the duplex drip-cups G and H, which are held united and set in communication with each other by means of the tubular arm a. The cup H is provided with a sleeve, b, fitted over the stand-pipe A and

held secured thereto by the set-screw I, which screw also allows of adjustment of the cups upon the stand-pipe A, as required. The fluid passes from the cups into the gage c, 55 and indicates the quantity of gasoline in the cups, which gage is arranged at a corresponding height to fill the cups sufficiently for a proper initial heating of the vapor-generators. Both the cups have perforations d 60 and e leading to the interior on a line little above the surface of the necessary quantity of fluid, as seen in Fig. 1. In addition to that, the central part of the cup G is formed into a tubular projection, f, with perforations 65 in the circumference thereof to admit air to the burning gasoline from the inside as well as from the exterior sides.

The upper part of the cup G is provided with a platform or receiver, g, as seen in 70 Figs. 1 and 2, into which the gasoline is conducted by the deflector E. At one side of this receiver is the conduit of the arm a, leading to the cup H, and directly opposite is the dam h, facing the cup G, as seen in Fig. 75

1. This receiver g is arranged for filling the cups G and H with fluid received from the needle-valve. The dam h causes the cup H to be filled first, and is arranged in such relation to the cup H as to assure a proper filling of said cup before the liquid will flow over the dam h down into the cup G—that is, the edge of the dam h is extended up from the receiver g, so as to be little below the horizontal plane of the lower end of the 85 perforations e, which prevents an overfilling of the cup H by enabling the continued stream of the fluid from the needle-valve to overflow into the cup G. As aforesaid, the level of the fluid in the cup G is indicated by 90 its reception in the gage c. The liquid when thus appearing in said gage gives notice to shut the needle-valve before it would run out through the perforations d. By these means and with little care the cups G H can 95 always be filled a certain quantity to assure a proper heating of the generators, and yet guard against overfilling or spilling of the gasoline.

The cups G and H will produce the same 100 described results when made in one piece equally well as when made in sections. (Shown

in Figs. 2 and 3.) The latter construction and arrangement, however, are preferred, in view of the means which admit of an easy separation of the parts for cleaning and removal of the 5 sediment, which may accumulate within cups while in practical operation, and of a ready readjustment thereof.

The gasoline is ignited at the receiver *g*, from which the flames will soon extend to the 10 cups *G* II and burn or consume the liquid therein without smoke, which is essential and an important feature in vapor-stoves, especially for domestic use. This is accomplished owing to the presence of the perforations 15 through said cups directly above the surface of the fluid, which in that instance is resultant in the admission of air, thus causing the vapor, which is rapidly generated, to ignite above the fluid, and as the flame rises the entire combustion thereof is completed by the air above. The specific gravity of the vapor being 20 comparatively so great, this process is not rapid, thus enabling oxygen to mix in sufficient quantity with the vapor to produce the desired result—that is, a smokeless flame. The confined space in which combustion takes place will not fully admit of the surrounding atmosphere to come in contact with it, suppressing to some extent the process of combustion, so 25 that the small amount of inflammable gas eliminated is readily and entirely consumed without smoke.

The combustion can be promoted or reduced by increasing or decreasing the depth of the 30 cups, and also by the size of the openings leading to the interior of the cups. To suppress the process of combustion sufficiently that the vapor can take in enough oxygen to produce a blue flame is an object of this invention. In the confined space of the cups combustion cannot take place on the surface of the fluid, but the flame is carried above it, resulting in the entire combustion of the vapor and gas in the confined space aforesaid and 35 on account of the depth of the cup. By this arrangement a sufficient amount of air is admitted to produce combustion without smoke.

This result is determined by actual tests, whereby I find that a slight variation in the depth of the cup will not change the result, 50 which consists in producing a blue flame by the means before described.

In vapor-burners provided with an ordinary drip-cup the smoke which issues from the burning gasoline covers up with soot more or less all parts which are within its influence about the stove, and the soot soon accumulates, so as to depreciate the appearance of the stove and is annoying to the operator while cooking.

What I claim, and desire to secure by Letters Patent, is—

1. As an improvement in vapor-stoves, the combination of the vapor-burner thereof with initial lighting devices having one or more 60 cups provided with openings or perforations in their sides located above the surface of the gasoline, substantially as and for the purpose set forth.

2. In combination with a vapor-burner, the 70 duplex cups *G* *H*, the receiver *g*, the dam *h*, separating said receiver from the cup *G*, and a passage, *a*, to the cup *H*, substantially as described.

3. In combination with a vapor-burner, initial lighting devices consisting of two cups, one of said cups being provided with a tube, *f*, in the center, said tube having an open bottom and a perforated upper portion, substantially as described.

4. In combination with a vapor-burner, the 75 duplex cups *H* and *G*, secured to the stand-pipe of said burner, said cup *G* consisting of sections, the lower section having perforations *d* in the sides and a tubular projection, *f*, and an adjustable connection between the upper and lower sections, substantially as and for the purpose set forth.

In testimony whereof I affix my signature in presence of two witnesses.

GEORGE W. BILLINGS.
